ABSTRACT OF THE DISCLOSURE

An apparatus for opening and closing a door panel which covers an aperture in a wall and which moves in a plane parallel to the plane of the wall. The motor and linkage elements for moving the door are substantially entirely located within a false lintel which comprises a portion of the wall opening.

Background of the invention

This invention relates to a door assembly and, more particularly, to a motor-actuated door for hatch openings. The invention is particularly suitable for operating the doors which cover relatively small openings such as hatchways for dumbwaiter installations and pass-through openings in a conveyor line. Separate motor and linkage arrangements are provided for each opening.

In prior art installations, dumbwaiter and pass-through conveyor doors are usually manually operated, since such doors are small and have low inertia. In many applications manually operated doors are suitable, but in many other instances it is highly desirable or necessary to provide motor-operated doors in installations where the operator has both hands otherwise occupied. Furthermore, motor-operated doors are necessary in automated conveying applications or where fire conditions and fire ratings are such that self-closing is required by means other than over-balance weights applied through release of a fusible fire link.

It has been proposed to provide power-operated dumbwaiter or pass-through doors by locating the motor and linkage mechanisms within the elevator hatch or on one side of the passthrough door opening. Such arrangements, however, are difficult to install and service, since it is necessary to perform installation and service operations within the hatch. Such operations are difficult, since there is no car platform to work from, as would be found in large freight or passenger elevator installations.

Summary

This invention overcomes many of these prior art problems, particularly those problems relating to the installation and servicing of motorized door operating mechanisms. The invention contemplates locating the motor and linkage elements for operating a vertically or laterally slidable door substantially entirely within the area of the wall opening so that such elements may be installed and serviced from the room side of the installation.

According to one aspect of the present invention, the door operating mechanisms are located substantially entirely within a false lintel which extends across the door opening.

Brief description of the drawings

FIG. 1 is an elevational view of a bi-parting type door employing a door operating mechanism according to one aspect of the present invention.

FIG. 2 is a fragmentary, cross sectional view of the door illustrated in FIG. 1, the plane of the section being indicated by the line 2—2 in FIG. 1.

2

FIG. 3 is a cross sectional view, the planes of the section being indicated by the line 3—3 in FIG. 2.

FIG. 4 is an enlarged front elevation of the operating mechanism according to this invention, with portions broken away for clarity.

FIG. 5 is a cross sectional view, the plane of the section being indicated by the line 5—5 in FIG. 4.

FIG. 6 is a fragmentary, cross sectional view, the plane of the section being indicated by the line 6—6 in FIG. 3.

10

Description of the preferred embodiment

Referring now to the drawings, a bi-parting door assembly 10 is illustrated. The door assembly 10 includes a pair of counterbalanced, vertically movable, bi-parting doors 11 and 12. The doors 11 and 12 are mounted for movement within a pair of U-shaped guide members 13 and 14 (FIG. 3). The guide members 13 and 14 are respectively mounted on a pair of side frame members 15 and 16. The side frame members 15 and 16 respectively cover the vertical faces 17 and 18 of an opening in a wall 20. The opening in the wall 20 is further defined by top and bottom faces 21 and 22 which are respectively covered by horizontal frame members 23 and 24. In an assembly employing a dumbwaiter elevator and wherein the opening in the wall 20 defines an access opening between a room and the elevator hatch or shaft, the guide rails 13 and 14, and therefore the doors 11 and 12, are mounted on the hatch or shaft side of the wall 20. A dumbwaiter elevator (not shown) would be mounted for vertical movement to clear the doors 11 and 12 during its travel in the hatchway.

A false lintel 25 extends across the upper portion of the opening defined by the side frame members 15 and 16 and by horizontal frame member 23. The false lintel 25 has a width which substantially corresponds to the thickness of the wall 20 and the false lintel 25 provides a shroud for a door operating mechanism which will now be described. A reversible motor 26 is supported by a bracket 27 which is fixed to an L-shaped hanger 28. The hanger 28 is fixed to a support plate 29 by bolts 30 which extend through the horizontal frame member 23. The motor 26 is connected to a reduction gear box 19 and the gear box 19 has an output drive shaft 31 which extends through an opening 32 in the bracket 28 and into a gear housing 33. The gear housing 33 is provided in the side frame member 16.

The end of the drive shaft 31 is provided with a spur gear 34 which is in driving engagement with a pinion gear 35. The pinion gear 35 is partially housed within the gear box 33, but has a portion which extends through an opening 36 in the gear box 33 and through an opening 37 in the U-shaped guide member 14. The peripheral portion of the pinion gear 35, which extends through the openings 36 and 37, engages a rack 38 which is mounted along one vertical side of the door 11.

The pinion gear 35 is pinned to a hub 39 which is mounted for rotation in a bearing sleeve 40. The bearing sleeve 40 is fixed to the end of the bracket 28. The hub 39 extends through the bearing and has a non-circular socket 41 which receives a drive shaft 42. The drive shaft 42 has a cross section which in the illustrated embodiment is square. The other end of the drive shaft 42 is received in a socket 43 which is provided in a hub 44. A spring 45 is provided in the socket 43 and biases the drive shaft to the right, as viewed in the drawings, and the drive shaft may be removed by axially displacing the shaft to the left against the bias of the spring 45 until the other end of the shaft 42 clears the socket 41.

The hub 44 is mounted for rotation in a bearing 46 which, in turn, is mounted on the lower end of a bracket 47. The bracket 47 is fixed to the support plate 29 by

70

bolts 49 which extend through the horizontal frame member 23. A pinion gear 50 is fixed to the end of the hub 44. The pinion gear 50 is substantially completely housed within a gear housing 51 which, in turn, is mounted within the side frame member 15. An opening 52 is provided in the side frame member 16 and in the guide track 13. A portion of the periphery of the pinion gear 50 extends through the opening 52 and engages a rack 53 which is vertically mounted along one side of the door 11.

The door 11 may be raised by causing the reversible motor 26 to drive the pinion gears 35 and 50 in a direction which will move the racks 38 and 53, and therefore the door 11, upwardly within the guide tracks 13 and 14. The motor 26 may be so actuated by pushing an "up" bottom (not shown). Similarly, the door 11 may be lowered by causing the motor 26 to reverse its direction to thereby drive the pinion gears 35 and 50 in a direction which will permit the racks 38 and 53, and therefore the door 11, to move downwardly. This may be accomplished by providing a "down" button (not shown) as a switch control for such a function of the motor 26.

The drive shaft 42 is provided with a cam drive gear 55 which is fixed to a middle portion of the shaft 42. An internally threaded member 57 is mounted on the drive gear 55. The member 57 is provided with an internal thread 58 which cooperates with a cam groove 59 on the drive gear 55. The member 57 carries a cam 60 and the cam 60 extends into a control box 61 through an elongated aperture 62 which extends in a direction which is parallel to the shaft 42. As the drive shaft is rotated in the directions previously indicated, the member 57, and therefore the cam 60, will move along aperture 62, since the aperture 62 prevents rotation of the member 57 with the drive gear 56.

As the door 11 is raised by the motor 26 and by the pinion gears 35 and 50, the cam 60 will move to the left, as viewed in FIG. 4, until it engages and closes a limit switch 61 which de-energizes the motor 26. A limit switch 61 is prepositioned relative to the cam 60 so that the motor 26 is de-energized when the door 11 is fully opened. Similarly, as the door 11 is closed by the motor 26 and the pinion gears 35 and 50, the cam 60 will move to the right, as viewed in FIG. 4, until the cam 60 engages and closes a limit switch 62 to thereby de-energize the motor 26. The limit switch 62 is pre-positioned relative to the cam 50 so that the switch 62 is closed by the cam 50 when the door 11 reaches its fully closed position.

As the door 11 is raised and lowered, the door 12 is correspondingly lowered and raised in the following manner. Sheaves 63 and 64 are respectively provided on the guide tracks 13 and 14. Each sheave 63 and 64 drives a chain 65 and 66 respectively and each chain 65 and 66 is connected at one end to a lower portion of the door 11 and at its other end to an upper portion of the door 12. The weight of the door 11 is slightly greater than that of the door 12 so that the door 12 acts as a counterweight for the door 11 and moves in a direction which is opposite to that of the door 11 as the door 11 is raised or lowered.

The gear ratio between the spur gear 34 and the pinion gear 35 is such that the motor 26 may be easily stalled if an object is accidentally inserted between the doors 11 and 12 during closure. The motor 26 may be provided with an overload cutoff (not shown) in the event that it is stalled in this manner. Moreover, the gear ratio between the spur gear 34 and the pinion gear 35 is such that the doors 11 and 12 may be manually operated when the motor 26 is not energized.

The door operating mechanisms are substantially entirely enclosed within a shroud which comprises the false lintel 25. The false lintel 25 is L-shaped and has a front face 71 and a bottom face 72. The front face 71 has an inwardly turned lip 73 which slips under the hori-

zontal frame member 23. The lip 73 is provided with slots (not shown) which engage a pair of guide pins 75 which extend downwardly from the plate 29. The bottom face 72 of the lintel 70 is bolted to end plates 76 which extend outwardly from each gear housing 33 and 51. Thus, the false lintel 70 may be easily removed from the assembly 10 to permit ready access to the door operating components.

The invention is not restricted to the slavish imitation of the details set forth above. Obviously, devices may be provided which change, eliminate, or add certain details without departing from the scope of the invention.

What is claimed is:

1. A motorized door assembly receivable in a door opening formed in a wall, which assembly comprises a relatively deep opening frame, at least one relatively shallow, vertically sliding door panel, guide rails for the door panel extending along a pair of hollow jamb members on a back side of the frame whereby the door panel may move vertically along said back side of the frame and is deeply inset from a front side of the frame, a powered door operating mechanism built in the head of the opening frame and completely within the frame outline, a false lintel extending along a true lintel of the frame between the hollow jamb members and concealing the door operating mechanism, the false lintel being at least partly removable from said front side of the frame to allow easy access to the operating mechanism for adjustment and maintenance from said front side of the frame, said door operating mechanism including drive pinion means within at least one of the hollow jamb members and mounted on a horizontal shaft extending between the hollow jamb members within the false lintel, rack means on the door panel engaged by the drive pinion means, and a motor within the false lintel for driving the pinion means, the shaft, and the rack means.

2. A motorized door assembly as set forth in claim 1 wherein the motor has a shaft which is positively linked in driving engagement with the rack means on the door panel through a linkage which includes the foregoing shaft and pinion means, the torque of said motor shaft and the gear reduction from said motor to said rack means being such that the energized motor may be stallable by manual restraint of the door panel, and the de-energized motor is readily rotatable by manual shifting of the door.

3. A motorized door assembly as set forth in claim 2 wherein said motor shaft is parallel to the horizontal shaft and wherein said linkage consists of said pinion means and a spur gear on the motor shaft engaging said pinion means.

4. A motorized door assembly as set forth in claim 1 wherein said motor control means includes a pair of limit switches for sensing fully open and fully closed conditions of the door, and reciprocating limit switch camming means driven by threaded engagement with means carried on said horizontal shaft.
